ELECTRICAL CUBICLE

Kibbey W. Couse, Newark, N.J., assignor to Couse Manufacturing, Inc., Newark, N.J., a corporation of New Jersey

Application August 12, 1958, Serial No. 52,185

Term of patent 7 years

(Cl. D26—5)

Fig. 1

Fig. 2

Fig. 1 is a front elevational view of an electrical cubicle, showing my new design:

Fig. 2 is a top plan view;

Fig. 3 is a rear elevational view; and

Fig. 4 is a side elevational view; the opposite side being substantially a mirror image thereof.

I claim:

The ornamental design for an electrical cubicle, as shown and described.
